COLUMBIA PLANOGRAPH CO., WASHINGTON, D. C.

UNITED STATES PATENT OFFICE.

LOUIS I. JACKSON, OF MUSKOGEE, OKLAHOMA, ASSIGNOR OF ONE-HALF TO EDWARD A. WETZ, OF MUSKOGEE, OKLAHOMA.

BED-TABLE.

1,051,597.

Specification of Letters Patent. Patented Jan. 28, 1913.

Application filed September 23, 1912. Serial No. 721,952.

To all whom it may concern:

Be it known that I, LOUIS I. JACKSON, a citizen of the United States, residing at Muskogee, in the county of Muskogee, State 5 of Oklahoma, have invented certain new and useful Improvements in Bed-Tables; and I do hereby declare the following to be a full, clear, and exact description of the invention, such as will enable others skilled 10 in the art to which it appertains to make and use the same.

This invention relates to combined dining tables and beds and has for an object to provide a device of this character which will 15 utilize the space between the underneath side rails of the table top to house the folding bed springs and mattress, and will have an extensible table top which is revolvably mounted on the legs, the device being converted 20 into the bed by simply rotating the table top and extending the same then unfolding the springs and mattress, this operation requiring minimum time and minimum manual labor, there being furthermore 25 more novel means for locking the parts in position to form either the table or the bed.

With the above objects in view the invention consists of certain novel details of construction and combination of parts herein- 30 after fully described and claimed, it being understood that various modifications may be made in the minor details of construction within the scope of the appended claims.

35 In the accompanying drawings forming part of this specification:—Figure 1 is a front elevation of the device as a table and with the legs moved outwardly to permit of the top being rotated to form the bed, the 40 latter position of the legs being shown in dotted lines. Fig. 2 is a front elevation of the device with the top rotated in an arc of one hundred and eighty degrees. Fig. 3 is a front elevation of the device with the 45 top extended and folding springs and mattress unfolded to form the bed. Fig. 4 is a plan view of the parts shown in Fig. 3 with portions of the mattress broken away. Fig. 5 is a longitudinal sectional view taken on 50 the line 5—5 Fig. 4. Fig. 6 is a cross sectional view taken on the line 6—6 Fig. 4. Fig. 7 is a cross sectional view taken on the line 7—7 Fig. 4. Fig. 8 is a cross sectional view taken on the line 8—8 Fig. 4, and

showing in dotted lines the table top in 55 normal position.

Referring now to the drawings in which like characters of reference designate similar parts, 10 designates a two piece table top having side rails 11 and end rails 12 60 run around the margin of the bottom face, the end rails being spaced inwardly from the end edges. This table top is mounted to turn on its central longitudinal axis between inverted U-shaped legs 13 arranged 65 at the opposite ends of the top, the extreme ends of the top bearing upon the top bars of the legs, as shown in Fig. 1, and holding the top against rotation. For pivotally attaching the top to the legs, a lug 14 is secured to the bottom face of the top bar of each inverted U-shaped leg, this lug being equipped with a pin 15 which projects across the edge of the adjacent end rail 12. A lug 15' is fixed to said end rail and is provided 70 with a tubular bearing 16 which loosely receives said pin. The pin furthermore is adapted to slide longitudinally through the bearing so that the related inverted U-shaped leg may be moved outwardly as 75 shown in dotted lines in Fig. 1 to clear the table top and permit of the latter being rotated on the pin. The lug 14 is provided on one side of the pin with a stop 17 which is adapted to engage in notches 18 on opposite 80 sides of the tubular bearing and limit rocking movement of the top in either direction as best shown in Fig. 8.

Disposed on the side and end rails are angle-iron extensible side rails 19 and end 90 rails 20 which fit in the corners formed at the meetings of the bottom face of the top 10 and side and end rails 11 and 12. The angle irons form a metal frame to which the folding bed springs are secured, the frame 95 being secured in place by screws 21 or the like passed through the angle-iron end rails and into the top. The extensible angle iron side rails 19 are each formed of two angle-irons 22 and 23 interfitting at their meeting 100 ends as shown in Fig. 7, a hook 24 being arranged on one of the angle-irons and fitting over the other angle-iron to slidably secure the angle-irons together. One of the angle-iron end rails is provided with spaced 105 bracket arms 25 which are secured to the underneath face of the adjacent half of the top as best shown in Fig. 4 to secure the

folding springs. The springs consist of two tubular U-shaped rods 26 and 27 the legs of which are pivotally connected together terminally as shown at 28 to permit one of the 5 rods being folded back upon the other, the rods when unfolded forming a rectangular frame which nicely fits within the angle-iron side and end rails as shown in Fig. 4. A plurality of longitudinal flexible cords 29 10 are secured terminally to the bights of the rods by helical springs 30, and transverse cords 31 are terminally connected to the sides of the rods, such cords forming a support for a mattress 32 which is connected to the cross members of the rods by cord loops 33. The cross member of one of the U-shaped tubular rods is fixedly secured in notches formed in the above mentioned bracket arms 25, whereby this rod is anchored. The free rod 27 may be folded back 15 upon the stationary rod with a resultant folding and confining of the mattress between the rods, and to hold the parts in this position a spring catch 34 is secured to the angle-iron end rail which carries the bracket arms 25, this catch hooking over the cross members of the said rod 27 and locking the 20 springs and mattress in folded position when it is desired to use the device as a table. A spring catch 35 is secured to the opposite angle-iron end rail and hooks over the cross member of the said rod 27 to hold the 25 springs and mattress in unfolded position to form a bed, there also being notched bracket arms 36 secured to this end rail on opposite sides of the catch to support the cross member of the said rod 27 when the 30 device is used as a bed.

For locking the top 10 against rotation 40 when the device is being used as a bed, a bolt 37 is slidably fitted in an opening 38 formed in one of the side rails 11 of the top and is adapted to be shot into an orifice 39 in the adjacent inverted U-shaped leg by 45 means of a pin formed integral with the

bolt as shown at 40 and projecting through the side of the opening 38. Furthermore, hooks 42 are secured to the rails as shown in Fig. 1 and are adapted to be engaged with pins carried by the adjacent leg. Thus the 50 top is provided with locking means on each side of the pivots thereof to positively hold the top against rotation when the device is used as a bed.

What is claimed, is:—

1. A combined table and bed including a table top, legs at the ends of said top, said legs normally contacting with the underneath edge portions of said top, means for sliding said legs outwardly beyond said top, 60 pivotal connections between said top and said legs permitting of said top being rotated through an angle of 180 degrees down between said legs when said legs are in their outermost limit of movement to form a bed, 65 and means for locking said top in position to form a bed.

2. A combined table and bed including an extensible table top, a folding frame secured to the underneath face of said top, a mattress secured to and adapted to be folded within said frame, inverted U-shaped legs at the ends of said table top, said legs normally contacting with the underneath edge 70 portions of said top, means for sliding said legs outwardly beyond said top, pivotal connections between said top and said legs permitting of said top being rotated through an angle of 180 degrees down between said legs when said legs are in their outermost 75 limit of movement to form a bed, and means for locking said top in position to form a bed.

In testimony whereof, I affix my signature, in the presence of two witnesses.

LOUIS I. JACKSON.
